UNITED STATES PATENT OFFICE.

JOHN J. GORMAN, OF CHICAGO, ILLINOIS.

DESIGN FOR A PROTECTIVE FOOT-PLATE FOR CARS, &c.

SPECIFICATION forming part of Design No. 30,270, dated February 28, 1899.

Application filed January 31, 1899. Serial No. 704,062. Term of patent 14 years.

To all whom it may concern:

Be it known that I, JOHN J. GORMAN, a citizen of the United States, residing at Chicago, in the county of Cook and State of Illinois, 5 have invented and produced a new and original Design for a Protective Foot-Plate for Cars, Steps, and other Objects, of which the following is a specification.

This invention relates to a new and original design for a protective foot-plate for cars, steps, and other objects; and it has for its object to provide a design of this character that shall be both useful and ornamental.

The leading feature of the design resides 15 in a rectangular plate-body provided with a scrolled edge.

A minor feature of the design is the rectangular plate-body provided therein with a plurality of circular holes and having the 20 scrolled portion at one of its longitudinal side edges.

Another minor feature of the design is the scrolled edge of the plate-body, having a V-shaped lobe centrally between the ends of the 25 plate and formed with a sigmoidal curvature at each side of said lobe.

In the drawings, Figure 1 is a perspective view of a protective foot-plate embodying the herein-described design. Fig. 2 is a plan view thereof.

Referring to the drawings, the numeral 1 designates a flat rectangular plate-body provided therein with a plurality of circular holes or openings 2 and at one of its longitudinal side edges with a scrolled portion 3. The 35 scrolled portion 3, at one side edge of the plate-body 1, is formed with a V-shaped lobe 4, projecting outwardly from the body at a point centrally between its ends, and at each side of said lobe the edge is sigmoidally curved 40 toward the ends of the body.

What is claimed is—

The design for a protective foot-plate for cars, steps and other objects, herein shown and described.

In testimony that I claim the foregoing as my own I have hereto affixed my signature in the presence of two witnesses.

JOHN J. GORMAN.
